UNITED STATES PATENT OFFICE

JOHN H. HOBBS, OF SYRACUSE, NEW YORK

DOOR AND FRAME GAUGE

Application filed September 19, 1929. Serial No. 393,740.

This invention relates to an especially designed gauge which is particularly adapted for use by carpenters in placing door frames or jambs and hanging swinging doors thereon.

Briefly stated, the improved appliance is characterized by a substantially rectangular adjustable frame, and supporting means therefor which is intended to be nailed or fastened in a temporary manner on the wall studding.

More specifically stated, I have evolved and produced a simple and economical appliance including a frame embodying spaced parallel side members which function as straight edges connected together by overlapping adjustably connected end members whereby to permit the area of the frame to be regulated at will, and said straight edge members are provided with spirit levels to permit the user to determine when the doorframe is plumb, thereby facilitating placement of the frame in a more satisfactory and accurate manner.

Other features and advantages will become more readily apparent from the following description and drawings:

In the drawings:

Figure 1 is a front elevation of an appliance constructed in accordance with the present invention.

Figure 2 is an end or edge view of the same.

Figure 3 is a top plan view.

Figure 4 is an enlarged transverse cross section on the line 4—4 of Figure 1.

Figure 5 is a longitudinal section through one of the adjustable end members.

Figure 6 is a perspective view of a resilient door frame retention clip.

Figures 7 and 8 are perspective views of certain of the details.

Referring now to the drawings in detail, and especially to Figure 1, it will be observed that the device comprises generally a frame indicated as a whole by the reference character 9. As before indicated, this comprises a pair of spaced parallel side members 10 and 11 functioning as straight edges and provided on their faces and intermediate their ends with ordinary spirit levels 12. These members 10 and 11 are joined together

through the medium of the adjustable end members 13 and 14 respectively. The end members are the same in construction, and a description of one will suffice for both. They include overlapping companion sections 15 and 16, one section being provided with beads 17 functioning as tongues and fitting in keyways provided by grooves in the complementary section.

The section 15 has a central longitudinal slot and a surrounding reinforcing wear plate 18 associated therewith. Threaded studs 19 are carried by the section 16 and extend through the slots and carry thumbscrews 20 which are tightened against the plate 18 to hold the same in overlapping adjusted relation. The sections 15 and 16 are preferably fastened by connecting screws 21 to the reduced end portions of the side members 10 and 11 as seen better in Figure 5. This renders a frame of the knock-down variety and facilitates storing, as well as transportation and handling.

As the normal position of the frame 9 is vertical as indicated in Figure 1, I employ the reference characters 22 and 23 to designate supporting or suspension devices. Each device comprises complementary strips 24 and 25 having apertured attaching ears 26 at their outer ends. The apertures are adapted to receive nails which are driven into the studding (not shown) in the wall structure. This provides a temporary means for suspending the frame 9 in a position to facilitate proper setting of the door frame (not shown).

The inner end of the bar members 24 and 25 are disposed in overlapping relation and coupled together through the medium of straps 27 provided with set screws 28. This allows the members 24 and 25 to be shifted longitudinally with respect to each other to permit proper nailing. The entire frame 9 is slidably mounted on the upper and lower suspension devices 22 and 23 and in this connection I provide brackets 29 at the opposite ends of the members 10 and 11 and attached to these are hangers 30 including guides through which the end portions of the members 24 and 25 pass. This allows the entire frame to be bodily shifted or the relative ad-

justable sections thereof to be moved with respect to each other to permit the desired plumb condition to be attained.

From the foregoing it will be seen that the frame comprises spaced parallel side members connected together by overlapping companion adjustable end members and that the entire frame is bodily and sectionally adjustable upon the upper and lower suspension members through the medium of the slidable 10 hanger construction.

The device is used as a square, a plumb, and a gauge. To begin with, the frame is nailed on the studding in the wall structure to dispose it in a vertical position. Before 15 nailing the frame in position, I have found it expedient and practical to nail the door frame (not shown) together and then slip the frame 9 snugly inside of the door frame, keeping the top of the appliance up tight 20 against the head jamb of the doorframe. Then the appliance, together with the frame, is nailed on the studding as described and adjusted back and forth until the door frame 25 is set plumb.

25 In this way the parts of the door frame can be properly disposed in accurate angular relation with respect to each other. Thus, much time and labor is saved, and more accurate work is insured.

30 To facilitate the hanging of the door frame on the frame 9, I have found it advisable to provide upper and lower pairs of clips generally designated by the reference characters 31. Each clip comprises an arm 35 portion 32 secured to a right angled bracket 33 carried on the rear side of the corner portions of the frame 9. Then too, there is a resilient retaining arm 34 having a flared extremity 35. These parts 34 and 35 permit 40 the side members of the door frame to be snapped into the clip to securely hold the door frame in place on the appliance.

I have found it practical also to detachably connect the aforesaid bracket 29 to the 45 members 10 and 11 by removable screws so that the frame 9 and the door frame may be bodily detached from the suspension means 22 and 23 then carried to saw bench and laid down on the door (not shown). Then the 50 operator may scribe a line all the way around the door frame and against the door to provide the desired mark, leaving a suitable clearance and to insure proper fitting of the door in its complemental door frame.

55 A careful consideration of the invention as explained in the description and shown in the drawings will enable the reader to obtain a clear understanding of the construction and use, and the features and 60 advantages thereof. Therefore, a more lengthy description is regarded as unnecessary.

Minor changes in shape, size, and materials coming within the field of invention

specified in the adjoining claim may be resorted to in actual practice if desired.

I claim:

In a structure of the class described, in combination, a pair of upper and lower suspension devices, each comprising a pair of bar members having its inner ends disposed in overlapping slidable relation and detachably connected together, apertured attaching ears at the outer ends of said bar members, a gauge frame comprising spaced elongated parallel side members joined together by overlapping adjustably connected end members, said end members being detachably connected to the opposite end portions of said side members, and hangers for attaching the side members to the bar members of said suspension device, said hangers including guide eyes through which said bar members are slidable.

In testimony whereof I affix my signature.

JOHN H. HOBBS.
